UNITED STATES PATENT OFFICE.

ADOLPH L. DE LEEUW, OF CINCINNATI, OHIO, ASSIGNOR TO THE CINCINNATI MILLING MACHINE COMPANY, OF OAKLEY, OHIO, A CORPORATION OF OHIO.

GEAR-CUTTER GRINDER.

1,078,540.

Specification of Letters Patent.

Patented Nov. 11, 1913.

Application filed May 27, 1913. Serial No. 770,172.

To all whom it may concern:

Be it known that I, ADOLPH L. DE LEEUW, a citizen of the United States, and residing at Cincinnati, in the county of Hamilton and 5 State of Ohio, have invented a new and Improved Gear-Cutter Grinder, of which the following specification is a full disclosure.

This invention deals with an instrumentality whereby gear cutters may be gradually sharpened so that similar points in the cutting edges of the several teeth will all be equidistant from the center and so that the grinding may take place in axial radial planes, thus preserving the contour of the 15 cutting edge.

One object within the contemplation of this invention is to create a simple mechanism of the above description adapted to be used as an attachment in connection with 20 any desired type of grinder, and which will represent a high order of manipulative convenience and be applicable for properly sharpening gear or other special cutters throughout a wide range of size.

25 Another object is to render available an attachment, for mounting a gear cutter which may be very easily set up, which will embody the features enabling its initial position relative to the grinding wheel to be 30 very accurately and easily obtained, and which will provide for an accurate positioning of successive teeth.

Other objects will be in part obvious from 35 the annexed drawings and in part indicated in connection therewith by the following analysis of this invention.

This invention accordingly consists in the features of construction, combination of parts, and in the unique relations of the 40 members and in the relative proportioning and disposition thereof; all as more completely outlined herein.

To enable others skilled in the art so fully 45 to comprehend the underlying features thereof that they may embody the same by the numerous modifications in structure and relation contemplated by this invention, drawings depicting a preferred form have 50 been annexed as a part of this disclosure, and in such drawings, like characters of reference denote corresponding parts throughout all the views, of which:—

Figure 1 is an end elevation of this attachment looking in the direction of the 55 plane of the grinding wheel showing the

rear end of the device. Fig. 2 is a top plan view of the attachment. Fig. 3 is a vertical axial section through line 3—3 of Fig. 2, *i. e.*, along the plane of the grinding face of the grinding wheel.

Referring to the drawings, A indicates the base of the attachment which is adapted to be secured to the table of a grinding machine, and which in turn revolubly supports the gear cutter. This base preferably provides lugs 1 in the nature of guides which are accurately aligned and are adapted to enter the T-slot in the table of a grinding machine. Slotted wings 2 are also provided for receiving bolts whereby the base is secured to the table. A stem or post 3 70 rises from the base A and is permanently secured in place by means of a nut 4 contained within an underlying recess 5 and in screw-threaded engagement with a shank 6 75 projecting through an aperture 7 in the base A. This aperture is preferably counterbored to receive the shoulder 8 of the post 3. At its upper end this post is provided with a collar or annular flange 9 serving as a table for supporting the cutter. A bushing 10 enables the cutter to be snugly seated on the projecting stud 11 of the post 3. The upper surface 12 of the base A is preferably flat and it provides a circular 85 portion 13 upon which are engraved the graduations 14 used in determining the initial relation between the base and an overlying member, as will be presently described. Projecting from one side of the base A is 90 a pin 15 which serves as a stop limiting the position of the overlying adjusting element, as will be explained.

Journalized on the post 3 and resting upon the top face 12 of the base A is a member B 95 which in turn carries three adjusting or positioning devices, viz: the initial positioner C for determining the initial position of the member B, a successive tooth positioner D, and a depth of cut determinator E. Of course, the member B instead of the base A may provide the mounting for the cutter to make it coaxial with the member B.

The initial positioner C comprises an arm 16 that has a slot 17 at one end and which 105 is adapted to receive a shank of a thumb screw 18 which enables said arm to be brought to a square seating on a boss 19 projecting from the member B. Extending at right angles to the arm 16 is a rod 20 110

preferably secured thereto by means of the nut 21 and terminating in a flat face 22. In setting up this device, this flat face 22 is brought into coincidence with the cutting plane of the grinding wheel, and the gage C may then be swung around to the other side of the attachment and out of the way. The gage surface 22 being coincident with the axial plane of the member B, radial cuts will be insured.

The tooth positioner D comprises a slotted element 23 adapted to be clamped in any desired angular position upon the shelf 24 of the member B by means of a thumb screw 25. The slot 26 enables it also to be adjusted longitudinally on the shelf 24. This element 23 carries a pawl 27 which is pivoted to its other end and which is normally maintained in definite relation with the element 23 by means of a spring 28 that swings the pawl 27 until it abuts against a part of the element 23. After the gage C has determined the setting of the instrument, a cutter tooth is brought into grinding relation with the grinding wheel and the adjuster D is set so as to bring the tip of the pawl 27 against the back of the tooth. A recess 33 enables the cutting wheel to clear the member B. After the tooth has been ground the cutter is turned by hand to bring the next tooth against the pawl 27 and its face is then ground, and so on in succession, until all of the teeth have been ground once around. It will be observed that this grinding is done in a truly radial direction. Should one or more of the teeth still be dull the member B, together with the pawl 27, may be swiveled to any desired extent about its axis so as to take off as much material during the next grinding operation as may be desired. To enable this accurately to be done, two screws 29 and 30 are carried by oppositely positioned ears 31 integral with the member B, so that the tips of these screws will press against the respective sides of the pin 15 projecting from the base A. The screw 30 preferably provides graduations 32 reading in thousandths of an inch, so that the user may be enabled to take off any exact amount of material. After the screw 30 has been operated, the screw 29 is tightened and the member B is locked in its new position, and the teeth of the cutter are then ground as before.

It will thus be seen that this invention is well adapted to achieve the objects and advantages enumerated in the foregoing. It is noteworthy, however, to obtain the best measure of advantage from this attachment it is advisable to use the same in standardizing new gear cutters to the attachment by first grinding the heel of each tooth, resting the pawl against its periphery close to the cutting edge so as to bring the backs of the teeth into a fixed relation with a uniform

section of the tooth form. With cutters so initially treated, the attachment insures a continuance of their cutting contours throughout their life.

Without further elaboration, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

Having thus described my invention, I claim as new and desire to secure by Letters Patent of the United States:—

1. A mechanism of the nature disclosed combining a base adapted to be secured to a machine and having an uprising cutter supporting post, a member pivoted about said post, an element providing a flat face in coincidence with an axial plane of said post, and a part carried by said member adapted to be contacted with the backs of the successive teeth of a cutter mounted on said post to bring each point of contact into the same definite relation with said member.

2. A mechanism of the nature disclosed combining a base member, an overlying member pivoted thereto, means for supporting a cutter in coaxial relation with said pivoted member, an element carried by said pivoted member and providing a gage surface in coincidence with a plane passing through the axis of said pivoted member, and a stop device adjustably and pivotally carried by said pivot member adapted successively to bring similar points in the backs of the teeth of the cutter into the same relation with the pivoted member.

3. A mechanism of the nature disclosed combining a base, a member swiveled thereto, means for supporting a cutter in coaxial relation with the pivot of said member, adjusting means for locking said member in a predetermined angular relation with said base, and a pivotal stop adjustably supported by said member adapted to coast with the backs of the teeth of a cutter at a fixed distance from the center thereof to bring the points of contact successively into definite relation with said member and swing aside to permit the teeth to be brought into grinding position by merely rotating said cutter.

4. A mechanism of the nature disclosed combining a base, a member swiveled thereto, an element carried by one of said parts and providing a gage surface in coincidence with an axial plane of said member, means for indicating a normal angular relation between said base and member and for lock-

ing the same in any angular relation therewith, and a stop device adjustably carried by said swiveled member adapted to abut the back side of each tooth in succession at 5 a fixed distance from the axis of said cutter.

5. A mechanism of the nature disclosed combining a base adapted to be secured to a machine and having an uprising cutter-supporting post, a member pivoted about said 10 post, an element providing a flat face coplanar with the axis of said post, a part carried by said pivoted member adapted to be contacted with the backs of the successive teeth of a cutter mounted on said post to 15 bring each point of contact into the same definite relation with said member, and adjustable means for determining the angular position of said member relative to said base.

6. A mechanism of the nature disclosed 20 combining a base member, an overlying member swiveled thereto, means for supporting a cutter in coaxial relation with said swiveled member, an element carried by one of said members and providing a gage surface 25 face in coincidence with an axial plane of said swiveled member, and a stop device adjustably carried by said swiveled member adapted successively to bring similar points 30 in the backs of each of the teeth of the cutter into an identical relation with the swiveled member.

7. A mechanism of the nature disclosed 35 combining a base, a member swiveled thereto, means for indicating when the axis of said member is exactly coplanar with the

grinding face of a grinding wheel, adjusting means for locking said member in a predetermined angular relation with said base, a stop adapted to be secured in definite relation with said member to coact with the 40 backs of the teeth of a cutter at a fixed distance from the center thereof to bring the points of contact successively into definite relation with said member, and a micrometer device for rotating said member through 45 a predetermined angle on said base to enable a definite amount to be ground off the face of each tooth of a cutter.

8. A mechanism of the nature disclosed combining a base, a member swiveled thereto, an element carried by one of said parts and providing a gage surface coplanar with the axis of said member, means for indicating a normal angular relation between said base and member and for locking the 50 same in any angular relation therewith, a thumb-screw for positively turning said member on its base, and a stop device adjustably carried by said swiveled member adapted to abut the back side of each tooth 55 in succession at a fixed distance from the axis of said cutter.

In witness whereof, I hereunto subscribe my name, as attested by the two subscribing witnesses.

ADOLPH L. DE LEEUW.
